UNITED STATES PATENT OFFICE.

EDWARD G. PARKHURST, OF HARTFORD, CONNECTICUT, ASSIGNOR TO THE PRATT & WHITNEY COMPANY, OF SAME PLACE.

FRICITION-HOLDFAST.

SPECIFICATION forming part of Letters Patent No. 341,500, dated May 11, 1886.

Application filed October 29, 1885. Serial No. 181,209. (No model.)

To all whom it may concern:

Be it known that I, EDWARD G. PARKHURST, a citizen of the United States, residing at Hartford, in the county of Hartford, State of Connecticut, have invented certain new and useful Improvements in Friction-Holdfasts, of which the following is a specification.

This invention relates to improvements in holdfasts for securing in any position within a specified amplitude the swinging part of a machine-gun mount, or of other similarly operated parts.

The object of the invention is to provide a powerful and compact apparatus operating by friction, and which may be operated from the lever whereby the swinging part is operated.

To this end the invention consists in the devices and combinations hereinafter set forth.

20 In the drawings accompanying and forming a part of this specification, Figure 1 is a side elevation of an apparatus embodying my invention. Fig. 2 is a vertical longitudinal section of the same. Fig. 3 is a vertical transverse section in line *a a*, Fig. 2. Fig. 4 is a perspective view of the wedge-ring. Fig. 5 is a perspective view of one of the two similar friction-plates.

Similar characters designate like parts in all the figures.

Any suitable base, A, varying in construction according to the situation in which the holdfast is to be applied, has rising therefrom two side walls, B B, which walls stand parallel to each other, and are prevented from spreading by the strong bolt N, having a head, 2, and a nut, 3, of the usual description.

Closely fitting between walls B B are the two similar parallel walls C C of the swinging frame F, which is pivoted on bolt N.

Between walls C C, and closely fitting bolt N, are placed, opposite to each other, two similar beveled-edge friction-plates, P, which are prevented from turning by a pin, 4, that fits closely in the holes 5, Fig. 5, in said plates, and is firmly driven into other holes in walls B B. This is shown best in Fig. 3. Said pin passes through slots in walls C C, so

that frame F is not thereby prevented from swinging through the required distance. 50 These slots are indicated by a dotted line at 6, Fig. 2.

The wedge-ring is designated by R, and is divided on one side at 7, on either side of which cut the ring has lugs 8 and 9. One of 55 said lugs, 8, is threaded to receive the correspondingly-threaded end 10 of shaft S, the other being bored, as at 11, Fig. 4. Said shaft has a bearing at 12 in the outer end of frame F, and is provided with a handle—as, for instance, H—whereby it is operated, and has a shoulder at 13, bearing against lug 9. On turning the shaft over toward the right-hand (when the thread on it is right-handed) the lugs are drawn together, thereby closing up 60 the wedge-ring, and forcing plates P apart and against walls C C, which in turn are sprung slightly apart firmly against walls B B. Thus by a single operation of the shaft are all the parts arranged about the bolt N 70 strongly clamped into one firm mass. On unscrewing the shaft S the ring R is allowed to expand by reason of its own elasticity. The plates and walls are thereby freed, and the frame F may then be swung up or down at 75 will by means of the same shaft used as a lever therefor. By means of this construction the swinging frame may be instantly clamped and unclamped, and very quickly changed from one position to another without letting go of the handle.

Having thus described my invention, I claim—

1. The combination, in a friction-holdfast, of a base having a pair of parallel walls, a swinging frame having parallel walls fitting within the base-walls, a pair of beveled oppositely-disposed friction-plates fitting between the frame-walls, a wedge-ring inclosing and operating to force apart said plates, a bolt 85 passing through said plates, frame-walls, and base-walls, and a shaft operating to close and uncloset said ring, substantially as set forth, and for the purpose specified.

2. The combination, in a friction-holdfast, 95 of a base having walls B B, a frame having

walls C C, plates P P, bolt N, and pin 4, and a wedge, substantially as described, forcing apart said plates, substantially as set forth.

3. The combination, in a friction-holdfast, 5 of a base having walls B B, a swinging frame having walls C C, and a bearing at 12 for shaft S, a friction apparatus, substantially as described, between walls C C, and a shaft, as

S, operating as a lever to swing the frame, and as a shaft to clamp and unclamp said apparatus, substantially as set forth.

EDWARD G. PARKHURST.
